ATTORNEYS

UNITED STATES PATENT OFFICE.

MOSES H. DURYEA, OF HACKENSACK, NEW JERSEY.

DESIGN FOR A POCKET SAFETY-CLIP FOR FOUNTAIN-PENS AND PENCILS.

No. 37,552.

Specification for Design.

Patented Sept. 12, 1905.

Application filed April 19, 1905. Serial No. 256,495. Term of patent 3½ years.

To all whom it may concern:

Be it known that I, MOSES H. DURYEA, a citizen of the United States, and a resident of Hackensack, in the county of Bergen and State of New Jersey, have invented a new, original, and ornamental Design for a Pocket Safety-Clip for Fountain-Pens and Pencils, reference being had to the accompanying drawing, in which the figure is a perspective view of a pocket safety-clip showing the design.

I claim—

The ornamental design for a pocket safety-clip for fountain-pens and pencils, as shown.

MOSES H. DURYEA.
